UNITED STATES PATENT OFFICE.

HARRY F. FISHER, OF ST. PAUL, MINNESOTA.

DWELLING INCINERATOR.

Application filed July 26, 1924. Serial No. 728,442.

My invention relates to an improvement in dwelling incinerators wherein it is desired to provide an incinerator of a design particularly adapted for use in dwellings and of a peculiar construction, which is of a simple design, yet providing a very effective and practical means of incineration in conjunction with the main chimney of the dwelling.

10 A feature of the invention resides in the circular construction of the combustion chamber of the incinerator, preventing air pockets and providing a combustion and reception chamber for the refuse, which permits of the most effective operation. This causes complete incineration of the refuse and overcomes the disadvantages where the incinerator is of a complicated design and wherein the walls of the incinerating chamber are formed with angular pockets instead of the circular dome-like construction which I have provided in my design of incinerator. It is a well recognized fact that the circular combustion chamber is more effective in operation and provides suitable means of draft through the chimney, which has a tendency to overcome and prevent down drafts which occur where pockets prevent the free draft of air in a circular manner up through the incinerating chamber and chimney.

15 The invention further provides a water coil within the combustion chamber of the incinerator which connects with the hot water system of the dwelling and which is operable by the incineration which ordinarily burns continuously in a large flat or dwelling with sufficient heat to operate the coil; and I further provide a gas or oil heater in connection with the water coil which can be operated to heat the water either in conjunction with the operation of the incinerator or independently.

20 In my incinerator the coil is designed to be positioned in the circular dome out of line with the flue opening of the chimney proper to permit the refuse to pass free of the water coil and gas heater. This is an important feature of my invention. The invention includes a grate set up in a manner to provide means for rotating the same

above the ash bed and set into the circular design of the fire pot with a peculiar construction and flange holding means which is associated with the fire brick in the most effective manner.

25 The features and peculiar construction, together with other objects and advantages of my incinerator will be more fully set forth in the following specification and claim:

Figure 1 is a side, sectional elevation of my incinerator and its connecting chimney as it would appear in use.

30 Figure 2 is a section on the line 2—2 of Figure 1.

Figure 3 is a section on the line 3—3 of Figure 1.

35 Figure 4 is a section of a portion of the operating grate of the incinerator.

40 Figure 5 is a section of the lower portion of the incinerator illustrating the grate, together with the clean-out door in the ash pit and the door into the fire compartment of the same.

45 My incinerator is formed with the combustion chamber 10, which is of a circular construction, in which the grate 11 is positioned in a manner so that it can be operated to dump the ashes into the ash pit 12 when desired by rotating the grate as illustrated in Figure 4. The ash pit is provided with a clean-out door 13 of ordinary construction, while the fire chamber or combustion compartment 11 is provided with a door 14 so that when it is desired the fire chamber can be reached through the door 14.

50 The grate 11 is of a circular construction with the holding lugs 15 formed on one side, which rest upon the shoulder 16 in the incinerator base. In the construction of the grate illustrated in Figures 3, 4 and 5 an annular flange member 17 is built into the base B of the incinerator A with the fire brick lining 18 built up and resting upon the horizontally extending annular lip 19 of the flange 17. This construction provides a grate for the incinerator A of a practical nature and of suitable strength so as to carry the load ordinarily required of an incinerator grate.

55 The grate 11 in Figure 1 is of a similar

construction excepting that the cast flange 17 is not present and the lugs 15 of the grate rest upon the metallic ring 20, which extends horizontally and upon which the fire brick lining rests at the bottom of the incinerator. The shaker rod 21 operates the grate in a rotary movement to dump the same.

The fire brick lining 18 is built up into the cylindrical portion C of the incinerator A to meet the dome portion D of the same. At the dome the incinerator is built into a conical formation and the fire brick 18 follows the inner contour of the same up to the main chimney E, which carries the ordinary flue lining as a protective medium for the lining of the chimney. The dome D is reinforced by metal rings 22 which are set in the brick walls of the dome in a manner so as to reinforce the same and give the necessary strength to provide a suitable base for the upper portion of the chimney E. This is an important feature of my incinerator as it permits the conical dome to be made in a manner so that the wall is not out of proportion with the base portion and to conform and blend into the formation of the chimney proper.

The incinerator A is designed so as to form a part of the chimney E and is used for the smoke pipe or chimney of the furnace by introducing in the dome the regular furnace smoke pipe 23 of ordinary construction, leading from the heating plant or furnace used in the dwelling.

Within the combustion chamber of the incinerator A, I position a water coil F which is provided with an inlet pipe 24 and an outlet pipe 25, so that water can circulate freely through the coil and the pipes 24 and 25 are connected with the hot water piping of the dwelling in the ordinary well known manner, not shown in the drawings. Directly beneath the coil F I provide a circular gas or oil burner G which is designed to heat the coil F when it is desired and the shut off valve 26 of which is placed at a distance from the incinerator body so as not to interfere with the incinerating operation when the gas or oil burner is not desired. The plug 27 closes the opening in the side of the incinerator wall and when it is desired to light the burner G this plug is removed and a flame introduced through the plug opening in a manner so as to properly ignite the burner G.

A feature of the invention resides in placing the coil F, which is circular in construction, out of line with the inside contour of the flue lining of the chimney as indicated by the dotted lines 28 in Figure 1 of the drawing. In this manner the refuse which is to be incinerated can be introduced into the chimney E and it will pass directly

through the coil F and on to the grate 11, without interfering with the coil F and the burner G.

In a flat or large dwelling where a great deal of refuse is collected and introduced into the incinerator A the same will continue to burn practically all of the time. Thus the coil F facilitates hot water being maintained for the flat so as to obviate the necessity of having a separate hot water heater. In connection with the coil F the incinerator can be fired by suitable fuel upon the grate 11 which is kept burning and which incinerates the refuse introduced into it as fast as it is dumped into the incinerating chamber, thus requiring but one heating medium for the incineration and for the hot water system. This is quite a saving in the summer months in the consumption of fuel in an apartment or dwelling where the incinerator is employed.

The gas burner G can be employed when the incineration is not sufficient to heat the water or when no incineration is in process. It is also obvious that the self same construction of the gas burner G can be used to introduce a liquid fuel such as coal oil or other suitable combustible liquid fuel which is sprayed onto the refuse, to be incinerated and thus the incinerator A will accomplish a very desirable result. This has proven to be a very satisfactory means of consuming large quantities of garbage or refuse which is constantly being introduced into the incinerator A. The spray of coal oil or liquid fuel forms a suitable means of combustion which has a great deal of heat units, tending to consume the refuse very rapidly so that the consumption of the same is complete, even though the refuse is wet when introduced into the incinerator A. This is an important feature of my invention and serves to provide a suitable heating means for the water coil F. The effective operation of my incinerator is apparent and the simplicity of construction is a marked advantage in the operation and cost of construction of my incinerator. The circular fire pot or combustion chamber, together with the conical dome prevent any pockets, and allow a clear uninterrupted draft which is highly important in the successful operation of a device of this nature, where the incinerator forms a part of the chimney for the dwelling to lead the smoke from the heating furnace and so that the drafts are unobstructed.

In accordance with the patent statutes I have described the principles of operation of my invention, together with the apparatus which I now consider to represent the best embodiment thereof, but I desire to have it understood that the construction shown in the drawings is only illustrative, and that the invention can be carried out by other

means and applied to uses other than those above set forth within the scope of the following claim.

I claim:

- 5 An incinerator including a combustion chamber, a chimney connected to said combustion chamber adapted to receive refuse therethrough and to carry off the gases from said combustion chamber, an opening in said

chimney to receive refuse into said incinerator combustion chamber, and a coil fuel oil burner extending into said combustion chamber in a manner to allow the refuse to pass therethrough and to spray fuel oil over the refuse introduced therein to consume entirely the refuse in said incinerator. 10 15

HARRY F. FISHER.
